UNITED STATES PATENT OFFICE

172,258

COMBINATION TABLE AND SLOT MACHINE

Albert Francois Villaudy, Los Angeles, Calif.

Application July 13, 1953, Serial No. 25,908

Term of patent 14 years

(Cl. D33—14)

To all whom it may concern:

Be it known that I, Albert Francois Villaudy, a citizen of the United States of America, residing in the city of Los Angeles, in the county of Los Angeles, State of California, have invented a new, original, and ornamental Design for a Combination Table and Slot Machine, of which the following is a specification, reference being had to the accompanying drawing, forming a part hereof.

Fig. 1 is a side elevational view of a combination table and slot machine showing my new design;

Fig. 2 is a top plan view thereof; and

Fig. 3 is a fragmentary end view thereof.

I claim:

The ornamental design for a combination table and slot machine, substantially as shown.
